UNITED STATES PATENT OFFICE.

FRANK C. PEASE, OF LATHAM, ILLINOIS.

OPERATING MECHANISM FOR SWITCHES.

Application filed July 6, 1922. Serial No. 573,094.

To all whom it may concern:

Be it known that I, FRANK C. PEASE, a citizen of the United States, residing at Latham, in the county of Logan and State of Illinois, have invented a new and useful Operating Mechanism for Switches, of which the following is a specification.

This invention relates to pressure controlled switches, and aims to provide novel means for automatically completing a circuit to a motor and simultaneously throwing in a clutch mechanism.

Another object of the invention is to provide a device of this character which will automatically break the circuit to the motor at a predetermined period.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a diagrammatical view disclosing a switch and clutch mechanism constructed in accordance with the present invention.

Figure 2 is a sectional view taken on line 2-2 of Figure 1.

Figure 3 is a sectional view through one of the switch members.

Figure 4 is a sectional view through the shaft housing.

Figure 5 is a sectional view taken on line 5-5 of Figure 4.

Referring to the drawings in detail, the reference character 5 designates an electric motor which is in circuit with a suitable source of electric supply, through the wires 6, 7 and 8, a manually controlled switch member 9 being interposed in the circuit for completing the circuit through the wire 6.

A power shaft 10 has connection with the motor shaft 11 as through the coupling 12, there being provided a clutch member 13 secured on one end of the shaft 10, which clutch member cooperates with the clutch member 14 for connecting the shafts 10 and 53. The clutch member 14 moves 55 on the shaft housing 53 and is normally held

in engagement with the clutch member 13 by means of the coiled spring 16.

The switch mechanism comprises a housing indicated generally by the reference character 17, which housing embodies a section 18 and a section 19, between which sections the diaphragm 20 is positioned. The section 19 is formed with a cut out portion to receive the head 21 formed at one end of the rod 22, which rod extends through an opening in the section 19 and has its outer end contacting with the pivoted bar 23, pivotally supported on the section 19 as by means of the pivot pin 24 mounted between the arms 25.

The bar 23 has an enlargement 26 formed adjacent to one end thereof, which enlargement accommodates the cup 27 that forms a seat for the coiled spring 28. The opposite end of the coiled spring 28 is received in the cup 29 supported by the section 18, there being provided a threaded bolt 30 passing through a suitable opening formed in the section 18, to contact with the cup 29. Due to the bolt 30, it is obvious that the tension of the coiled spring 28 may be regulated to cause the bar 23 to operate under various degrees of pressure.

The bar 23 is formed with an opening to accommodate the bolt 31 that has one end positioned in a suitable threaded opening in the section 19, whereby the outer end of the bar 23 may be held against lateral movement with respect to the section 19 to insure a true operation of the bar.

Pivotedly connected to the bar 23 as at 32, is an arm 33 that carries a roller 34 at the outer or free end thereof, the arm 33 moving over the inclined surface 35 of the head 36 formed in the clutch bar 37.

This clutch bar 37 is shown as pivotally supported by the section 18 as at 38 to permit of a free pivotal movement of the bar 37 with respect to the body portion of the device.

A threaded rod 39 is supported by the section 18 and passes through a suitable opening in the bar 37, whereby the bar 37 is held against lateral movement.

Carried by the bar 37 at a point adjacent to the head 36 is an insulating block 40 that carries a switch plate 41 that is in circuit with the wire 8 forming the ground circuit. A similar insulating block 42 is mounted on the section 18 and carries a switch arm 43

constituting the stationary element of the switch, the arm 33 being curved to lie in the path of travel of the switch plate 41, when the bar 37 moves towards the body portion 17.

A coiled spring 44 has connection with the arm 33 and has one end anchored to the section 18, so that the arm 33 is normally held under tension, to the end that the roller 10 34 is forced against the inclined surface 35.

In order that the bar 37 will be retarded in its movement in one direction, a coiled spring 45 is interposed between the clutch bar 37 and insulating block 42, so that when 15 the clutch bar moves inwardly, such movement is made against the tension of the spring 45.

The clutch bar 37 is formed with an offset portion 46 that has its outer end forked 20 as at 47 to move in the groove 48 forming a part of the clutch member 14 so that movement of the clutch bar 37 results in a relative movement of the clutch member 14, to throw the same into and out of operation.

25 As shown, the section 18 is formed with a cut out portion 49 providing a compartment for the reception of water which is forced through the pipe 50, when the tank not shown, and which is in communication 30 with the pipe 50, is being filled with water. When the water within the compartment 49 reaches a predetermined degree of pressure, it is obvious that the diaphragm will move laterally, causing the head 21 to move the 35 rod 22 outwardly forcing the arm 33 laterally, moving the roller 34 over the cam surface 35 allowing spring 44 to move arm 33 inwardly camming clutch bar 37 in direction of the arrow as shown by Figure 3 of the 40 drawings, to the end that the circuit to the motor is broken, cutting off the motor and simultaneously moving the clutch members out of engagement.

45 As the water pressure within the compartment 49 is reduced, the spring 28 will overcome the tension of the spring 44 forcing the arm 33 towards the clutch bar 37 and moving the roller 34 over the cam surface 35, to the upper portion thereof.

50 The spring member 45 moves the clutch operating bar 37 inwardly until the switch member 41 again contacts with the switch

member 43, closing the circuit to the motor to cause the same to cause the operation of the shaft 10 and housing 53.

55 Mounted on one end of the shaft 10 is a pulley 51 which may have connection with a suitable pump or other suitable machinery not shown. The housing 53 also supports the pump chambers 51 in which operate rotary pumps not shown. While I have described the operation and construction of one of the switch members as shown in Figure 1 of the drawings, it is to be understood that switch members of this character may 60 be duplicated throughout the length of the shaft for operating additional pumps and various types of machinery.

65 It might be further stated that the shaft 10 operates in suitable bearings 52 supported in the housing 53 or shaft.

Having thus described the invention, what is claimed as new is:—

70 In a device of the character described, a propelling shaft, a propelled shaft associated with the propelling shaft, a clutch for clutching the shafts together, an operating means including a diaphragm housing, a diaphragm in the housing partitioning the housing into lateral compartments, a pipe 75 extending into the housing and adapted to feed fluid to one side of the diaphragm, a rod extending into the housing and carrying a head engaging one side of the diaphragm, an arm pivotally supported on the 80 housing and adapted to be engaged by the rod to move the arm in one direction, a pivoted bar on the arm, a coiled spring having connection with the bar for normally urging the bar towards the housing, a relatively 85 large coiled spring engaging the arm and adapted to normally urge one end of the arm away from the housing and overcome the tension of the first mentioned spring, and means operated by the movement of the arm 90 for moving the clutch to its active position. 95

In testimony that I claim the foregoing as my own, I have hereto affixed my signature in the presence of two witnesses.

FRANK C. PLEASE.
